UNITED STATES PATENT OFFICE.

ELIAKIM M. VAN PELT, OF ELIZABETH, AND RALPH H. DIXON, OF NEWARK, NEW JERSEY.

COAL-SAVING DEVICE.

Application filed August 18, 1924. Serial No. 732,698.

To all whom it may concern:

Be it known that we, ELIAKIM M. VAN PELT and RALPH H. DIXON, citizens of the United States, residing at Elizabeth, in the 5 county of Union and State of New Jersey, and at Newark, county of Essex, and State of New Jersey, have invented certain new and useful Improvements in Coal-Saving Devices; and we do hereby declare the following to be a full, clear, and exact description of the invention, such as will enable others skilled in the art to which it appertains to make and use the same, reference being had to the accompanying drawings, 10 and to characters of reference marked thereon, which form a part of this specification.

This invention relates, generally to improvements in fuel-saving devices; and the present invention has reference, more particularly, to a novel and simply constructed device, made of any non-inflammable material, and of any suitable shape, for use of the device with any form of coal-burning apparatus, resulting in a saving in the consumption of the coal.

The present invention has for its principal object, the provision of a coal-saving means for coal-burning furnaces, and the like, made, preferably, in the form of a disc 30 of a non-inflammable material, adapted to be placed upon the bed of burning coal of any stove, furnace or similar heating unit, the device being provided with an escape means for the gases arising from the fuel-bed, so as to permit such gas or gases to commingle with air above the fuel-bed, and to thereby provide a complete burning of the arising gases, which heretofore escaped with a consequent loss in heat units.

Other objects of the present invention not at this time more particularly enumerated will be clearly understood from the following detailed description of the present invention.

With the various objects of the present invention in view, the said invention consists, primarily, in the novel coal-saving device hereinafter more fully set forth, for use with any form of heating apparatus, 50 the device being made of a non-inflammable material, and while usually of a circular shape, may be made in any other suitable shape, so as to be properly fitted within and conform to the shape of the fire-box or 55 interior of the stove, furnace, or other heat-

ing unit, with which the device is to be used.

The invention is clearly illustrated in the accompanying drawings, in which:

Figure 1 is a side elevation of a furnace, 60 with a portion of its wall being represented broken away, showing a portion of the fuel-bed, with the coal-saving device placed in its operative position upon the bed of fuel.

Figures 2 and 3 are a plan and bottom view, respectively, of a coal-saving device, 65 showing one embodiment of the principles of the present invention; Figure 4 is a side elevation of the device; Figure 5 is a transverse sectional representation of the same; 70 and Figure 6 is a detail vertical section, taken on line 6-6 in Figure 2, said view being made on an enlarged scale.

Figure 7 is a view, similar to Figure 4, 75 of a slightly modified construction of coal-saving device; Figure 8 is a bottom view of another modified form of coal-saving device, but still embodying the principles of the present invention; and Figure 9 is an end-edge view of the device shown in said Figure 8.

Similar characters of reference are employed in all of the said above described views, to indicate corresponding parts.

Referring now to the several figures of the drawings, the reference-character 1 indicates a heater of any one of the usual constructions, 2 is the usual fire-box, and 3 is the grate, upon which is located a fuel 4, such as coal.

Upon this bed of fuel, after the same has been lighted, and is burning freely, may be placed a coal-saving device of the general construction illustrated in the several figures of the drawings, the device being inserted 95 into the firebox of the furnace or heater, through the usual fire-box door 5.

In Figures 2, 3, 4 and 5 of the drawings, 100 is illustrated one form of coal-saving device, the same comprising a circular body-element or plate 6, made of a non-inflammable material, such as asbestos, or the like, the said body-element or plate 6 being provided with a preferably centrally disposed opening 7, surrounded by an upwardly projecting marginal flange 8, providing with said opening 7 a suitable gas-flue for conducting the unburnt gases from the bed of fuel, above the said body-element or plate 6, into the fire-box or chamber 2 of the furnace, 110

as will be understood from an inspection of Figure 1 of the drawings. The said marginal flange 8, as will be evident, is also made of a non-inflammable material.

5 Suitably disposed upon the lower surface of the said body-element or plate 6, are ribs or battens, as 9, these being arranged substantially as shown in Figure 3 of the drawings, and being of such width, that, 10 when arranged in the manner illustrated in said Figure 3, suitable gas-conducting spaces 10 in communication with the main opening 7 will be provided. Thus, when the device has been placed upon the ignited bed of 15 fuel, with the ribs or battens 9 serving as supports for the body-element or plate 6, the spaces 10 located between said ribs 9 provide suitable chambers in which the gas or gases are collected, to be conveyed 20 through the conducting spaces, into and through the flue to be delivered into the fire-box or chamber 2, and thereby commingling with the air to be ignited and consumed, resulting in the complete burning of 25 the arising gases. One method of securing the said ribs 9, which are also made of a non-inflammable material, to the under side of the body-element or plate 6, is by means of suitably constructed pins or rivets 12, 30 but it will be understood that the said ribs or battens may be suitably secured to the said body-element or plate 6 by moulding or otherwise.

While in the construction illustrated in 35 Figures 2, 3, 4 and 5 of the drawings, the said ribs or battens 9 are shown of a square or rectangular shape in cross-section, it will be evident that the said ribs or battens may be otherwise shaped, as indicated in Figure 40 7 of the drawings, the body-element or plate 6 of the device being provided in this case with ribs 13 which are V-shaped in cross-section.

When the coal-saving device is to be used 45 with heaters or furnaces having a square or rectangular grate-surface, then the device may be made as indicated in Figures 8 and 9 of the drawings, in which case the reference-character 14 indicates a non-inflammable body-element or plate of a rectangular shape, provided with a centrally disposed opening 15, surrounded by a marginal flange 16. Upon its lower surface, the said body-element or plate is provided with laterally 50 extending supporting ribs 17, provided with channelled or cut out portions, as 18, for the passage of the gas or gases therethrough, and into the gas-flue formed by said opening 15 and the flange 16, as will be clearly 55 evident from an inspection of said Figures 8 and 9.

From the foregoing description of the present invention it will be seen that we have devised a simply constructed and an 60 effective coal-saving device made of a non- 65

inflammable material, and conforming to the shape of the inside of any coal-burning furnace, or similar heat-producing unit, the device being readily placed directly upon the fuel-bed, the gas-opening of the device 70 being properly placed so as to freely permit the gases from the fuel to escape to the space above the fuel-bed, and there to become ignited. In that case, therefore, all the gases which heretofore escaped with a 75 loss of the heat-giving units, are entirely consumed, resulting in an increased efficiency of the heat-producing unit, and a consequent saving in the consumption of the 80 fuel.

Of course, we are aware that some changes may be made in the general arrangements and combinations of the several parts comprising the herein-described non-inflammable coal-saving device, without departing 85 from the scope of the present invention, as set forth in the foregoing description of the same. Hence, we do not limit ourselves to the exact arrangements and combinations of the various parts as described in the said 90 specification, and as illustrated in the accompanying drawings.

We claim:

1. A coal-saving device comprising a body-element made of a non-inflammable material, said device being adapted to be placed upon the bed of fuel of a heat-producing unit, supporting ribs extending from the lower face of said body-element, said ribs being also made of a non-inflammable 95 material and being arranged, when the device is placed upon the bed of fuel, to provide gas-collecting spaces, and the said body-element being further provided with means for conveying the unconsumed gases from 100 said collecting spaces for consumption above the said body-element.

2. A coal-saving device comprising a body-element made of a non-inflammable material, said device being adapted to be placed upon the bed of fuel of a heat-producing unit, supporting ribs extending from the lower face of said body-element, said ribs being also made of a non-inflammable 110 material and being arranged, when the device is placed upon the bed of fuel, to provide gas-collecting spaces, and the said body-element being further provided with an 115 opening and an upwardly extending marginal flange surrounding said opening, all 120 arranged to provide a flue into and through which the unconsumed gases are conveyed from said collecting spaces for consumption above the said body-element.

3. The herein-described coal-saving device 125 comprising a body-element made of a non-inflammable material, said body-element being provided with a centrally disposed opening, ribs disposed upon the lower surface of said body-element, said ribs being also 130

made of a non-inflammable material, said ribs radiating outwardly from said opening, the said ribs being arranged to provide with the body-element a plurality of gas-collecting spaces, and a means of communication between said gas-collecting spaces and the said opening for conveying the collected gases above said body-element.

4. The herein-described coal-saving device comprising a body-element made of a non-inflammable material, said body-element being provided with a centrally disposed opening, ribs disposed upon the lower surface of said body-element, said ribs being also made of a non-inflammable material, said ribs radiating outwardly from said opening,

the said ribs being arranged to provide with the body-element a plurality of gas-collecting spaces, a means of communication between said gas-collecting spaces and the said opening, and a marginal flange surrounding said opening and forming in connection therewith a flue, all arranged for conveying the collected gases above said body-element.

In testimony that we claim the invention set forth above we have hereunto set our hands this fourteenth day of August, 1924,

ELIAKIM M. VAN PELT.
RALPH H. DIXON.
